UNITED STATES PATENT OFFICE

166,667

OCTAGON TABLE FRAME

Lester Grundy, Glen Rock, N. J., assignor to Molla Incorporated, Westbury, N. Y., a corporation of New York

Application January 11, 1951, Serial No. 13,745

Term of patent 14 years

(Cl. D33—14)

To all whom it may concern:

Be it known that I, Lester Grundy, a citizen of the United States, now residing at Glen Rock, in the county of Bergen and State of New Jersey, have invented a new, original, and ornamental Design for an Octagon Table Frame, of which the following is a specification, reference being had to the accompanying drawing, forming part thereof.

The figure is a perspective view of an octagon table frame, showing my new design.

I claim:

The ornamental design for an octagon table frame, as shown.

LESTER GRUNDY.
